United States Patent Office

Des. 186,675
Patented Nov. 17, 1959

186,675

REPEATER POPGUN

Earl H. J. Lohaus, St. Louis, Mo.

Application June 22, 1959, Serial No. 56,471

Term of patent 14 years

(Cl. D34—15)

Fig. 1

Fig. 2

Fig. 3

Fig. 4

Fig. 1 is a side elevational view of a repeater popgun showing my new design;

Fig. 2 is a bottom plan view thereof;

Fig. 3 is a front elevational view thereof; and

Fig. 4 is a rear elevational view of the same.

I claim:

The ornamental design for a repeater popgun, as shown.
